 Western Electric Company, Incorporated, New
 York, N. Y., a corporation of New York

Application November 26, 1948, Serial No. 62,153

6 Claims. (Cl. 242—45)

1

This invention relates to apparatus for equalizing tension in material pulled from a rotatable supply of the material and has for its object a sensitive mechanism affected by variations in the pull on the material at the supply to create constant tension in the material.

The speeds at which material handling machines may operate depend largely upon the efficiency of the mechanisms associated therewith in controlling the tensions in the materials. During unwinding of sheet material from a supply roll, by pulling the material from the supply, there will exist the problem of the gradually diminishing diameter of the supply roll effecting a gradual increase in tension. During unwinding of strand materials from reels the effective variations in the supplies on the reels occur only at the end of one layer of convolutions and the beginning of another layer. This factor is more disturbing than the gradual increasing of tension in the sheet material in that there is a tendency for the strand material to be shocked by these sudden changes resulting in possible damage to the strand material if a highly sensitive mechanism is not provided to allow for these abrupt attempts to vary the tension in the material.

With the aforementioned object in view, the invention comprises an apparatus for equalizing the tension in material pulled from a rotatable supply of the material, the rotation of the supply resulting from the pull on the material being removed from the supply. The apparatus is employed in combination with a variable displacement fluid piston motor-pump having a shaft rotatable about a fixed position axis and a compensator variable with variations of tensions in the material to act as a controlling factor. The tension equalizing apparatus includes a cradle supported for rocking movement about the axis of the shaft and is formed to receive a spindle for removably supporting the supply of material. The material supply is caused to rotate with the spindle and a unit is variable, depending on the tension to be created in the material pulled off the supply, to normally urge the cradle in a direction opposite the direction of pull of the material on the supply. A mechanism operatively connecting the spindle and the shaft causes variation of the pressure of the fluid in the control motor-pump unit with variations of the tension in the material, and as a result of the motor-pump unit will act as either a motor or a pump to correct such irregularities in tension.

2

More specifically, the cradle is substantially U-shaped in general contour, the upper ends of the vertical portions being formed to removably receive the spindle, whereby the reel or supply of material may be readily loaded in the cradle and urged into its starting position by the pulling force of the variable tension setting unit. The tension setting unit contains a helical spring connected at one end to the cradle, whereby a predetermined force comparable to the tension to be created in the material is applied to the carriage in a direction opposite the pull of the material from the supply.

Other objects and advantages will be apparent from the following detailed description when considered in conjunction with the accompanying drawings, wherein

Fig. 1 is a front elevational view of the apparatus;

Fig. 2 is a side elevational view of the apparatus, portions thereof being removed; and

Fig. 3 is a fragmentary sectional view taken along the line 3—3 of Fig. 1.

Referring now to the drawings, the apparatus includes a cradle 10 which is U-shaped in general contour, one leg 9 of the cradle carrying a stub shaft 11, journaled in a bearing 12, mounted upon a vertical member 14. The other leg 15 of the cradle supports a housing 16 through which a shaft 17 extends in axial alignment with the shaft 11. The outer end of the shaft 17 is journaled in a fixed position bearing 18 mounted upon a vertical member 19 while the inner end of the shaft is journaled in the leg 15.

The shaft 17 has a pinion 20 mounted thereon and interengaging a gear 21 of a shaft 22. The pinion 20 and the gear 21 are disposed in a housing 16, the open end of the housing being closed by a cover 24 which is provided with suitable bearing portions for the outer ends of the shaft 22 and also a shaft 25. The inner ends of the shafts 22 and 25 are journaled in the leg 15 of the cradle 10. The shaft 22 has a sprocket 26 mounted thereon which is operatively connected to the shaft 25 through a chain 27 and a sprocket 28, the latter being mounted on the shaft 25. A handle 29 formed integral with the housing 16 projects outwardly therefrom, as illustrated in Fig. 2 and is provided with an indicating point 30 at the outer end thereof.

The shaft 25 extends inwardly through the housing 16 and has an enlarged portion 31 disposed in the notched upper end 32 of the leg portion 15 of the cradle 10 and has a recess 33 therein. A spindle 34 is positioned in the hub

of a reel 35 of strand material 36, the spindle having a conical portion 38 to cause centering of the spindle in the reel. The spindle is also provided with a pin supporting flange 39 for engagement with the reel. The innermost portion 40 of the spindle is receivable in the recess 33 of the shaft 25 (Fig. 3) when the reel with the spindle is positioned in the cradle 10. The other end of the spindle 34 has a threaded portion 41 upon which a nut 42 is mounted removably securing the spindle within the reel. The extreme outer end 43 of the spindle is removably journaled in a bearing 44 disposed in a notched outer end 45 of the adjacent leg 9 of the cradle 10.

A hood-like casing 48 mounted on a suitable support 49 partially houses the reel when loaded in the apparatus, the sides 50 and 51 of the casing being cut away at 52 to allow movement of the cradle with the reel from the loading position shown in broken lines in Fig. 2 to the starting position shown in solid lines in this figure. A latch 53 pivotally supported at 54 on the side 51 of the casing 48 is normally disposed in the position shown in Fig. 2 with its lip portion 55 disposed in the path of the side 9 of the cradle 10 to hold the cradle with the reel against movement into its loading position. A handle 56 of the latch projects outwardly whereby the operator may readily actuate the latch when it is desirable to unload the empty reel. Arcuate portions 57 of the cut away portions 52 serve to hold the ends of the spindle in the notched ends 32 and 45 of the cradle 10.

A tension setting unit 60 is mounted on the side 50 of the casing 48, this unit including a dial 61 graduated to represent variable forces to be applied to the cradle through a cable 62 connected to the handle 29 by a coupling 63. The cable 62 is connected to an inner structure of the unit 60 which includes a helical spring (not shown), the force of which may be varied by moving the dial 61 relative to a pointer 64. The pull on the handle 29 tending to rotate the cradle with the reel counterclockwise into the position shown in solid lines in Fig. 2 will assist in determining the tension to be maintained in the strand material 36 as it is pulled off the reel 35.

The apparatus thus far described is used in combination with a unit 66 commercially known as a variable displacement piston pump-motor controlled by a pressure actuated compensator as shown in detail in Patent 2,351,264 to F. T. Harrington et al. of June 23, 1944. The unit 66 is adapted to operate either as a pump or motor depending upon conditions within the fluid line 67 affected by the connection of the unit to the shaft 17 through its output shaft 68 and coupling 69.

Considering now the operation of the apparatus, it will be understood that a full reel 35 of strand material 36 may be readily loaded into the apparatus by first mounting the spindle 34 in the reel and locating the cradle 10 in the broken line position shown in Fig. 2. The reel 35 may be rolled on the support or floor 49 until the spindle is received in the cradle and is properly connected to the shaft 25 through the members 31 and 40. By the aid of the handle 29 the cradle with the reel may be moved about the axes of the shafts 17 and 68 into the position shown in solid lines in Fig. 2. The tension to be established in the strand material 36 depends largely upon the size, weight and strength of the material. In the present embodiment of the invention, the material 36 is electrical cable which may

vary in these characteristics depending upon the number of insulated electrical conductors assembled in the cable. It is therefore arranged that the tension to be created in the material will be such that during normal operation of the apparatus for medium or heavy reels, the pointer 30 on the handle 29 will register with a point 70 on the side 50 of the casing, this being the vertical position of the cradle.

The unit 66, that is, the pressure actuated compensator 72 thereof is adjusted before the strand material is pulled off the reel. Therefore, when the pulling operation starts, the reel will be moved with the cradle against the force embodied in the unit 60 until the cradle is in its operating position with the marks 30 and 70 registering. If the diameter of the reel or the lever arm at the point of take off of the material from the reel remained unchanged, the unit 60 perhaps could function in maintaining the predetermined tension in the material. However, the lever arm or the effective diameter of the reel diminishes as each layer of material is removed therefrom, tending to increase the tension in the material. During rotation of the reel, in a clockwise direction (Fig. 2) the shaft 25 is rotated in the same direction causing its sprocket to move the chain 27 to rotate the shaft 22 in the same direction. The shaft 22 will drive its gear 21 to drive the pinion 20 with the shaft 17 in a counterclockwise direction, this driving force continuing through the coupling 69 and the shaft 68 into the unit 66. By prearranged setting of the pressure actuated compensator 72 of the unit 66, it is intended that a predetermined pressure be maintained in the unit. An increase of tension in the material will be translated through the reel and the connecting mechanism to the unit 66, causing an increase in the pressure in the unit. The compensator 72 will be affected by this increase in pressure in the unit 66 and will convert the unit from a pump to a motor, driving the connecting mechanism leading to the reel until the predetermined tension has again been established in the material and the predetermined pressure in the unit 66 has again been established. If for any reason the tension in the material should be reduced, the connecting mechanism between the reel and the unit 66 would affect reduction in the pressure in the unit 66. The compensator 72 would then cause the unit to speed up its pumping action until the pressure therein has reached the prearranged pressure affecting a drag on the shaft 17, which would be translated through the connecting mechanism to the reel until the slack in the material has been removed and the prearranged tension established.

The tension equalizing apparatus employed in combination with the unit 66 provides for the automatic reduction of the pump to the constant volume requirement of the power pump at a maintained predetermined pressure. Therefore, during the operation of the apparatus, as the payoff reel decreases in diameter, it will increase in speed as a result of the constant linear velocity of the material. The constant volume requirement of the unit 66 will immediately create a pressure rise tendency as a result of the increased speed of the unit. This pressure rise tendency will immediately cause tension control response to vary the compensator 72 of the unit 66 in the direction of decreasing angular displacement with increasing speed for a constant volume output at maintained pressure.

A sudden slackening of the cable tension permits the reel cradle 10 to swing backward under the pull of the unit 60. This action causes the epicyclic gearing arrangement to speed up the pump temporarily increasing its braking action and slowing down the reel. A sudden tightening of the cable temporarily speeds up the reel. The slightest change in the cable tension instantly starts corrective measures to restore the initial set tension. An arcual displacement of the cradle and reel from the operating position cushions the sudden change in the cable tension. Furthermore, an instantaneous but temporary speed-up or slow-down of the unit 60 takes place to decelerate or accelerate the reel rotation.

To achieve a more sensitive control of light tensions of smaller cables or strands on lighter and smaller reels, it will be advantageous to have the operating position of the cradle 10 forward of the dead center position with registration of the points 30 and 70 for the medium or heavy reels. As a result, the force of gravity exerted on the reel and cradle when moving in the general direction of the cable pull will assist in providing a softer cushioning effect against over-tension in the cable. In addition to this, the accelerating force of gravity will compensate for the tension increase which occurs in the hold back spring of the unit 60 for the reel cradle. The slower action of the reel cradle retarded by gravity, in its backward travel to take up cable slack prevents over correction when attempting to take up excessive slack. This will prevent sudden and wide swaying of the tension control medium and will therefore indirectly prevent excessive tension in the cable. The gradual decreasing weight of the light reel, due to the paying off of the light cable will permit a rightening of the reel cradle and cause it to assume operating positions closer to its vertical or dead center position. This will tend to retain the same reel torque condition from the start to the finish of cable un-winding from the reel.

It is to be understood that the above described arrangements are simply illustrative of the application of the principles of the invention. Numerous other arrangements may be readily devised by those skilled in the art, which will embody the principles of the invention and fall within the spirit and scope thereof.

What is claimed is:

1. An apparatus for equalizing the tensions in materials pulled from rotatable supplies of materials, in combination with a variable displacement fluid piston motor-pump unit having a shaft rotatable about a fixed position axis and a compensator variable with variations of tensions to be created in the materials to maintain a selected variable pressure of the fluid in the motor-pump unit comparable to the tensions to be created in the materials, the apparatus comprising a cradle supported for rocking movement about the axis of the shaft into and out of an operating position, a spindle for supporting a supply of material, mounted for rotation on the cradle, means to connect the supply of material to the spindle whereby the spindle will be rotated with the supply when the material is pulled therefrom, means variable, depending on the tension to be created in the material pulled off the supply, to normally urge the cradle with the supply in a direction opposite the direction of the pull of the material from the supply, and means operatively connecting the spindle and the shaft whereby movement of the cradle

out of its operating position, as a result of variation of the tension in the material from a pre-determined tension, will cause variation in the pressure of the fluid in the unit rendering the compensator effective to cause the unit to affect the rotation of the supply to change the tension in the material to the said predetermined tension.

2. An apparatus for equalizing the tensions in materials pulled from rotatable supplies of materials, in combination with a variable displacement fluid piston motor-pump unit having a shaft rotatable about a fixed position axis and a compensator variable with variations of tensions to be created in the materials to maintain a selected variable pressure of the fluid in the motor-pump unit comparable to the tensions to be created in the materials, the apparatus comprising a cradle supported for rocking movement about the axis of the shaft into and out of an operating position, a spindle for supporting a supply of material, mounted for rotation on the cradle, means to connect the supply of material to the spindle whereby the spindle will be rotated with the supply when the material is pulled therefrom, means variable, depending on the tension to be created in the material pulled off the supply, to normally urge the cradle with the supply in a direction opposite the direction of the pull of the material from the supply, and a mechanism operatively connecting the spindle and the shaft whereby movement of the cradle in one direction out of the operating position by an increase of the tension in the material will cause the unit to function as a motor to drive the shaft, the mechanism and the spindle with the supply until the tension in the material is reduced to the predetermined tension.

3. An apparatus for equalizing the tensions in materials pulled from rotatable supplies of materials, in combination with a variable displacement fluid piston motor-pump unit having a shaft rotatable about a fixed position axis and a compensator variable with variations of tensions to be created in the materials to maintain a selected variable pressure of the fluid in the motor-pump unit comparable to the tensions to be created in the materials, the apparatus comprising a cradle supported for rocking movement about the axis of the shaft into and out of an operating position, a spindle for supporting a supply of material, mounted for rotation on the cradle, means to connect the supply of material to the spindle whereby the spindle will be rotated with the supply when the material is pulled therefrom, means variable, depending on the tension to be created in the material pulled off the supply, to normally urge the cradle with the supply in a direction opposite the direction of the pull of the material from the supply, and a mechanism operatively connecting the spindle and the shaft whereby movement of the cradle in one direction from the operating position by the said pulling means as a result of a decrease in tension in the material will cause the unit to function as a pump creating a drag on the shaft, the connecting mechanism, the spindle and the material until the tension in the material is returned to the predetermined tension.

4. An apparatus for equalizing the tensions in materials pulled from rotatable supplies of materials, in combination with a variable displacement fluid piston motor-pump unit having a shaft rotatable about a fixed position axis and a compensator variable with variations of tensions to

be created in the materials to maintain a selected variable pressure of the fluid in the motor-pump unit comparable to the tensions to be created in the materials, the apparatus comprising a U-shaped cradle supported for rocking movement between a loading position and the operating position about the axis of the shaft into and out of an operating position and having spindle supporting recesses in the upper ends thereof, a spindle, for supporting a supply of material, removably mounted in the recesses of the cradle, means to connect the supply of material to the spindle whereby the spindle will be rotated with the supply when the material is pulled therefrom, means variable, depending on the tension to be created in the material pulled off the supply, to normally urge the cradle with the supply in a direction opposite the direction of the pull of the material from the supply, and means operatively connecting the spindle and the shaft whereby movement of the cradle out of its operating position, as a result of variation of the tension in the material from a predetermined tension, will cause variation in the pressure of the fluid in the unit rendering the compensator effective to cause the unit to affect the rotation of the supply to change the tension in the material to the said predetermined tension.

5. An apparatus for equalizing the tensions in materials pulled from rotatable supplies of materials, in combination with a variable displacement fluid piston motor-pump unit having a shaft rotatable about a fixed position axis and a compensator variable with variations of tensions to be created in the materials to maintain a selected variable pressure of the fluid in the motor-pump unit comparable to the tensions to be created in the materials, the apparatus comprising a U-shaped cradle supported for rocking movement between a loading position and the operating position about the axis of the shaft into and out of an operating position and having spindle supporting recesses in the upper ends thereof, a spindle, for supporting a supply of material, removably mounted in the recesses of the cradle, means to close the recesses to maintain the spindle therein, means to connect the supply of material to the spindle whereby the spindle will be rotated with the supply when the material is pulled therefrom, means variable, depending on the tension to be created in the material pulled off the supply, to normally urge the cradle with the supply in a direction opposite the direction of the pull of the material from the supply, and means operatively connecting the spindle and the shaft whereby movement of the

5 cradle out of its operating position, as a result of variation of the tension in the material from a predetermined tension, will cause variation in the pressure of the fluid in the unit rendering the compensator effective to cause the unit to affect the rotation of the supply to change the tension in the material to the said predetermined tension.

10 6. An apparatus for equalizing the tensions in materials pulled from rotatable supplies of materials, in combination with a variable displacement fluid piston motor-pump unit having a shaft rotatable about a fixed position axis and a compensator variable with variations of tensions to be created in the materials to maintain a selected variable pressure of the fluid in the motor-pump unit comparable to the tensions to be created in the materials, the apparatus comprising a U-shaped cradle supported for rocking movement between a loading position and the operating position about the axis of the shaft into and out of an operating position and having spindle supporting recesses in the upper ends thereof, a spindle, for supporting a supply of material, removably mounted in the recesses of the cradle, a hood having arcuate portions to effectively close the recesses to maintain the spindle therein, a latch carried by the hood to limit the cradle from movement into the loading position, means to connect the supply of material to the spindle whereby the spindle will be rotated with the supply when the material is pulled therefrom, means variable, depending on the tension to be created in the material pulled off the supply, to normally urge the cradle with the supply in a direction opposite the direction of the pull of the material from the supply, and means operatively connecting the spindle and the shaft whereby movement of the cradle out of its operating position, as a result of variation of the tension in the material from a predetermined tension, will cause variation in the pressure of the fluid in the unit rendering the compensator effective to cause the unit to affect the rotation of the supply to change the tension in the material to the said predetermined tension.
